CENTRIFUGAL PUMP

Elmer R. Wilfley and John L. Aldred, Jr., Denver,
Colo., assignors to A. R. Wilfley and Sons, Inc.,
Denver, Colo., a corporation of Colorado

Application September 28, 1949, Serial No. 118,236

2 Claims. (Cl. 103—103)

1

This invention relates to centrifugal pumps. In the installation of such pumps, difficulties are encountered especially when they must be placed in a hemmed-in or crowded environment, due to the fact that intake and discharge pipe connections for the pump must be arranged to suit a given disposition of the intake and discharge necks of the pump housing. These necks are usually integral parts of certain castings which constitute the housing and which are such that the pipe connections must be suited to the pump necks.

It is an object of this invention to provide a pump which is versatile in the sense that it minimizes such installation problems, and to provide a pump in which the intake and the discharge necks are adjustable to suit individual local conditions and to simplify the disposition and arrangement of the corresponding pipe connections.

In order to attain this object of this invention the pump housing is subdivided and arranged in a novel manner whereby the intake as well as the discharge necks are angularly adjustable with respect to each other as well as with respect to the frame or base of the pump.

According to one feature, the housing comprises an intermediate vertical annular frame portion rising from a base, and a pair of complementary housing portions in the form of half-shells each of which is fastened to a respective side of the annular frame portion. The one half-shell having an inlet neck represents the intake portion of the housing providing an annular low pressure chamber at the low pressure side of the pump. The opposite half-shell having a discharge neck represents the discharge portion of the housing and it provides the high pressure chamber that houses the impeller. Bearing means for the impeller shaft extend centrally into the inlet portion of the housing in sealing relationship therewith. The inlet portion is rotationally adjustable upon the annular frame portion about the bearing means, so that the inlet neck can be adjusted to a selected annular position.

According to a more specific feature, the base or casting is formed with the intermediate annular frame portion as well as with supporting means for the outer end portion of the impeller shaft, the inner end portion being supported by the adjustable intake portion of the housing.

It is an example and in no limiting sense that the improvements in the construction of the pump housing are herein shown to be embodied in that class of centrifugal pump known as sand pumps or slurry pumps which serve for handling

2

corrosive liquids or liquids carrying grit or sand constituents. Such pumps avoid the use of a frictional seal or stuffing box between the impeller shaft and the intake portion of the pump housing by providing an annular valve member which normally closes an annular non-frictional clearance or gap between the impeller shaft and the housing while the pump is not running. This gap is automatically opened when the pump starts running, is kept open while the pump is running, and is again closed when the rotation of the impeller shaft stops. Leakage of liquid through the annular clearance is counteracted by a suitable hydraulic sealing pressure created by the rotation of the pump impeller itself.

Therefore, this invention is shown herein as embodied in a sand pump such as exemplified in the patent to Wilfley No. 1,976,532 in which an axially non-shiftable impeller shaft is surrounded by an annular sealing valve member which is axially shiftable upon the shaft for opening or closing the annular gap around the impeller shaft.

In this patent, the operation or shifting of the sealing valve member is effected automatically by control mechanism whereby the valve member is normally held weighted upon and in sealing relationship with the housing by spring pressure when the pump is not operating. When the impeller shaft starts rotating, a set of centrifugal weight members will operate to retract the valve member from its seat upon the housing against the pressure of the spring, the valve thus to remain open while the pump is running. Leakage through the annular clearance is counteracted by an auxiliary or sealing impeller which is co-axial and rotating unitary with the impeller shaft and which while rotating creates hydraulic pressure opposing the tendency of leakage of liquid or slurry through the annular gap. When the pump stops running, the valve member shifts due to the spring pressure now closing the gap, as the hydraulic sealing pressure from the auxiliary impeller dies down along with the disappearance of the centrifugal forces which actuate the mechanism.

Such a valve control mechanism from the Patent No. 1,976,532 is herein shown as part of the structural and operational environment of this invention, but the details of that mechanism per se do not constitute a part of this invention.

The best embodiment of this invention now known to us is described herein by way of example but it is not to be taken as limiting because obviously changes can be made therein so

long as they do not depart from the scope of the appended claims, remembering, however, the patent law principle of equivalents.

In the drawings:

Fig. 1 is a part-sectional longitudinal side view of the pump unit.

Fig. 2 is an exploded view of parts of Fig. 1 illustrating the improvements in the construction of the pump housing.

Fig. 3 is a view of the discharge side of the pump housing indicating the angular adjustability of the pump outlet.

Fig. 4 is a view of the intake side of the pump housing indicating the angular adjustability of the pump inlet.

The pump unit comprises a frame member in the form of a casting 10 which in turn comprises the longitudinal body portion 11, an annular upright portion 12 rising from one end of the base portion and defining a plane extending transversely of the base portion, and further comprises a bearing-sustaining portion herein also termed a bearing lug 13 which rises from the other end of the body portion 11.

The pump housing comprises a pair of half-shells 14 and 15 complementary to each other and fastened to the annular upright portion 12 which thus forms an intermediate portion of the housing. The one half-shell 14 represents an inner housing portion herein also termed the intake portion of the housing provided with an intake neck 14^a (see Fig. 3). The other half-shell 15 represents an outer housing portion herein also termed the discharge portion of the housing which is provided with a discharge neck 15^a (see Fig. 2). The intake portion of the housing is the low-pressure housing portion, while the outer or discharge portion is the high-pressure housing portion.

The pair of the half-shells 14 and 15 is fastened as by bolts to opposite sides of the upright portion 12, and an annular member 16 is interposed between the discharge housing portion 15 and the upright portion 12. The discharge housing shell 15 has lugs 17 whereby it is held to the upright portion 12 by fastening bolts 18. These bolts are shown to be spaced, for example, 90 degrees apart from one another, so that the discharge neck 15^a can be adjusted (see Fig. 5) to different angular positions at 90 degree intervals.

The intake housing shell 14 has fastening bolts in the form of countersunk screws 19 shown to be spaced from one another at 45° intervals so that the intake neck 14^a can be adjusted angularly in accordance with that spacing of the bolts.

The intake housing shell 14 resembles a hollow annular member open inwardly and having an inner vertical annular wall portion 18^a held to the upright portion 12 by the countersunk screws 19, and surrounding the inner portion 16^a of the intermediate annular member 16. The intake housing shell 14 has an outer wall portion 20 provided centrally with an opening 21 into which fits and through which extends a shaft-carrying horizontally extending stationary structure collectively designated as 22. Thus the inner end of this shaft-carrying structure 22 is supported by the intake housing shell 14 through annular members M and M₁ which in turn fit into the opening 21, the members M and M₁ being secured to structure 22 as by countersunk screws 21^a.

The outer end of the structure 22 is supported by the bearing lug 13 upon which it is held down by a bearing cover 23 bolted to the lug. Longitudinally the position of the shaft-carrying struc-

ture 22 is fixed, although adjustably, relative to the frame member 10 and thus relative to the stationary parts of the pump unit by means of a stud 24 extending horizontally and parallel to the longitudinal axis of the structure 22, the stud 24 being screwed tightly into the bearing lug 13 so as to be unitary therewith. The stud 24 in turn extends through a lug or forked lateral extension 25 of the shaft-carrying structure 22, and a pair of nuts 25^a and 25^b upon the stud engage the lug 25 thereby anchoring and fixing the shaft-carrying structure 22 in an adjusted position relative to the stud 23 and thus relative to the base or stationary parts of the pump unit.

The shaft-bearing structure 22 extending into the intake housing shell 14 has sealing relationship therewith due to the provision of a packing gland 26 comprising a gland member 27 held in place and under suitable pressure by retaining lugs 28 which in turn are held by screws 29 upon the intake housing shell 14.

An impeller 30 surrounded by the discharge housing shell 15 is mounted upon the outer end of an impeller shaft 31 and secured thereon as by a retaining bolt 32. This impeller is formed with and terminates rearwardly in an extended and widened or flaring hub portion which constitutes an auxiliary or sealing impeller I having impeller blades B. The shaft is carried by a pair of ball bearings 33 and 34 provided within the structure 22. The structure 22 comprises a shaft-bearing section 35 and a control section 36 containing the control devices for actuating the sealing means described further below. The shaft-bearing section 35 comprises a cylindrical member 37 in which are mounted the ball bearings 33 and 34 which in turn carry the impeller shaft 31. The control section 36 comprises a cage member 38 open at the bottom and having a flange connection 39 with the cylindrical member 37, and also comprises the control device proper indicated at C. The inner end of the cage member 38 is closed by annular member M which is marginally sealed against the intake housing shell 14 through the packing gland 26, and thus although removable represents a part of the inlet portion of the pump housing. The annular member M is finished off inwardly, that is towards the interior of the pump housing by a contour face 42 so-termed because it provides the contour face 42 as part of the interior contour of the intake portion of the pump housing. The annular member M has an annular recess R into which extends and in which rotates the auxiliary impeller I, there being a clearance between the impeller and the member M.

Facing the cage 38 the annular member M has a valve seat 50 upon which engages an annular sealing valve member 51 which is axially shiftable to and from its seat by the control mechanism C. This control mechanism comprises a sleeve 52 fixed upon the shaft 31 and formed at its outer end with a labyrinth flange 53 formed outwardly with concentric labyrinth portions 54 and 55 lodging in corresponding annular recesses formed in or by the end portion 56 of cage 38.

The valve member 51 while axially slidable upon the sleeve 52, is unitary with a cup 57. A flexible annular diaphragm or septum 58 interconnects the cup 57 with the sleeve 52 so that the cup constitutes a chamber 58^a which houses the centrifugal device proper that effects the shifting of the valve member 51 unitary with the cup 57.

A set of centrifugal weight members 59 (of which only one is shown) are carried by the sleeve 52 which in turn rotates with the shaft 31. These weight members are pivotally mounted as at 60 so that their outer weighted ends 59^a may swing outwardly due to centrifugal force set up by rotation of shaft 31, while their inner ends 59^b engage upon an internal spider 61 unitary with cup 57 and shift the cup together with the valve member away from the pump housing against the pressure of a compression coil spring 62 confined between the spider 61 and the labyrinth flange 53.

Operation

When the shaft 31 starts rotating, the centrifugal members will swing outwardly and move the valve member away from its seat just sufficiently to avoid frictional contact, while compressing the spring 62. Vice versa, when the shaft stops rotating, the centrifugal forces will die down so that the pressure of spring 62 will cause the weight members to return while shifting the valve member to close upon its seat on the pump housing. As the valve member 51 and cup 57 are thus being shifted, the diaphragm member 58 deforms accordingly, all the while serving to protect the centrifugal mechanism within the cup against liquid that may leak past the annular valve seat of the pump when the valve opens or closes.

What we claim is:

1. A centrifugal pump comprising a body portion, an upright portion which is integral with and extends upwardly from said body portion, an opening in said upright portion, a pair of complementary housing portions in the form of half-shells, said half-shells being carried by opposite sides of said upright portion, one of said half-shells forming a discharge housing and the other half-shell forming an intake housing, a rotating

impeller shaft extending through said intake housing shell and into said discharge housing shell, a center intake impeller mounted on the discharge housing end of said shaft and rotatable therewith, an annular member disposed between said discharge housing shell and said upright portion and secured to one side of the upright portion, said annular member having a central portion which extends through the opening in said upright portion and which telescopes within said intake housing shell, the annular member having a central opening communicating with the intake housing and the impeller, thus providing an interconnecting passageway therebetween for conducting fluid to said impeller.

2. A pump structure as defined in claim 1 in which the intake housing shell and the discharge housing shell are secured by equi-angularly spaced fastening means whereby the housing shells are angularly adjustable relative to each other.
